(57) CLAIM

The ornamental design for a dispenser housing, as shown and described.

DESCRIPTION

FIG. 1 is a perspective view of a dispenser housing showing my new design;

FIG. 2 is a right side view thereof;

FIG. 3 is a left side view thereof;

FIG. 4 is a top view thereof; and,

FIG. 5 is a front view thereof.

The broken line showing of various features is for illustrative purposes only and forms no part of the claimed design. The remainder of the dispenser including its bottom and rear forms no part of the claimed design.
